UNITED STATES PATENT OFFICE.

DONALD McGREGOR NEWTON, OF MONTCLAIR, NEW JERSEY, ASSIGNOR TO
MACARTHUR CONCRETE PILE & FOUNDATION CO., INC., OF NEW YORK,
N. Y., A CORPORATION OF DELAWARE.

METHOD OF FORMING PILING.

Application filed November 14, 1924. Serial No. 749,893.

This invention relates to piling and to the erection of the same, and more particularly to composite piles and to the formation thereof.

6 An object of the invention is to provide an improved method whereby a pile may be put in place.

A further object is directed to the provision of a simple and comparatively inexpensive method of forming a strong and durable pile.

10 A still further object is that of providing a method whereby a pile of the above mentioned type may be formed in soils wherein 15 the water-line is below the surface of the ground.

Another object is predicated to the provision of a composite pile wherein the several parts are positively interlocked.

20 Other objects of the invention will in part be obvious and will in part appear hereinafter.

The invention accordingly comprises the several steps and relation and order of one 25 or more of such steps with respect to each of the others, and the article possessing the features, properties, and the relation of elements, which are exemplified in the following detailed disclosure, and the scope of the 30 application of which will be indicated in the claims.

For a fuller understanding of the nature and objects of the invention, reference should be had to the following detailed description taken in connection with the accompanying drawings, in which:

Figures 1 to 7 illustrate successive steps in one method of forming a pile according to the invention; and

40 Fig. 8 illustrates one type of pile contemplated by the invention such as may be formed by the method illustrated in Figs. 1 to 7.

The apparatus employed in the present 45 exemplification of the invention includes a hollow casing 10 and a rod-shaped ram 11. The casing illustrated consists of a tubular shell 13 having at its upper end a reinforcing band 14, at the top of which there is 50 formed an inwardly extending flange 15 which serves as an abutment engaging the top of the shell 13. The ram may comprise a stem 16, the base 17 of which is shaped to fit snugly within the interior of

the casing and is formed so as to provide 55 a flat compacting surface 17' at its lower end. At the top of the stem 16 there is provided a head 18, including a shoulder 19 which is adapted to engage the upper end of the casing—in the present instance, the 60 flange 15—when the base 17 is adjacent the lower end of the casing with the flat surface 17' in the same plane with the lower surface of the casing. At the top of the head 18 there is provided a cushioning block 65 20 adapted to receive blows from a pile driver of the usual type, or to have pressure applied thereto by any suitable mechanism for the motivation of the ram.

In the present instance, there is illustrated a method which is especially suitable for the formation of a composite pile in soils in which comparatively poor strata overlie strata of sufficient firmness to support piles and structures superimposed 75 thereon and in which the water-line is below the surface of the ground. In the drawings there is shown the stratum of a relatively firm soil extending below the division line 25 and a stratum of weaker soil such as mud or soft earth extending upwardly from line 25, the latter stratum containing ground water which rises therein to a line indicated by the division line 22. It will be appreciated, however, that this method may be 80 varied considerably in accordance with the type of soil in which the pile is to be formed and with the type of pile itself.

According to the method proposed, the ram is inserted in the casing and moved 90 downwardly therein, the shoulder 19 serving as a stop when the flat surface 17' is in line with the base of the casing. The ram and the casing having been set on the ground, pressure is thereafter applied to the cushioning block 20 by any suitable means and the ram and casing are simultaneously sunk into the ground to any desired depth, which in the present instance is preferably about 4 feet below the water-line indicated at 22. 95 The ram is then withdrawn from the casing and a solid pile member 23 inserted therein. It will be appreciated that this pile member may, as a general rule, consist of a wooden pile of the ordinary type. In the method 100 illustrated, after the pile member 23 has been inserted in the casing, the ram 11 is 105 allowed to rest thereon and pressure is again

applied to the cushioning block 20 to drive the ram and the pile member downwardly through the casing and to force the lower end of the pile member into the stratum of firm soil illustrated at 25. It will be noted that the lower ends of the base 17 is beveled at 26, so that when the upper end of the solid pile member protrudes from the top of the casing in the manner shown in Fig. 2, the ram will be guided by the beveled portion so as readily to follow the pile member into the bore of the casing during the operation just described. The beveled portion 26 will, of course, also assist in the introduction of the ram into the casing at other times. It will, moreover, be apparent that during the sinking of the solid member 23 the casing will serve to guide this member so that it may be sunk in a substantially straight line. Thus when any obstructions, such as large stones, are encountered by the pile member during its downward movement, the casing will prevent this member from being so diverted from its path of movement by these obstructions as to form a substantial angle with the casing and hence with the vertical bore in which the upper portion of the pile is to be formed. The disadvantage of having such an angle in the completed pile will be obvious, since the weight superimposed on the pile would tend to break it at such an angular joint. As a general rule, the casing will hold a pile member such as 23 with sufficient firmness so that this member will force the obstruction from its path; but, even though this is not the case, it will prevent the pile member from forming an angle with the casing, in which, in the present instance, the upper portion of the pile is to be formed, and will insure either that the operator will be aware of the obstruction, or, at the worst, that a substantially straight although somewhat oblique pile will be formed.

After the solid pile member has been sunk to the proper distance, the ram is, in the present instance, again withdrawn from the casing and a foundation material in a plastic state, such as the concrete indicated at 27, is introduced into the casing, only the lower end thereof being filled with this material in the particular method illustrated. The ram is then inserted within the casing and allowed to rest upon the upper surface of the foundation material with its flat surface 17 in contact therewith, so as to exert a compacting pressure thereon; whereupon the casing is partially withdrawn as indicated in Fig. 5 and pressure again applied to the ram so as to force the material downwardly into the cavity left by the withdrawal of the casing and outwardly into the surrounding soil so as to form a head such as indicated at 28 in Fig. 5, which completely encloses the upper end of the solid pile mem-

ber and which, after the hardening of the concrete or other plastic material, will securely grip this member positively to lock the lower and upper members of the composite pile against relative movement. In the formation of this head, as in the preliminary boring operation, the shoulder 19 acts to prevent the ram from being moved through the casing further than its position as shown in Fig. 1, so as to prevent the base 17 from protruding into the mass of concrete below the casing and forming an indentation therein into which, upon the withdrawal of the ram, the surrounding concrete will tend to fall loosely, thus weakening the head and allowing the surrounding soil to fall about the same and to mix with the concrete thereof. Obviously, types of joints other than the head 28 may be employed to interlock the upper and lower portions of the pile. For example, one end of the solid member may be tapered and the other member formed about its tapered end.

The method under consideration contemplates the withdrawal of the ram from the casing after the formation of the head 28 and the introduction into the casing of a column of concrete extending sufficiently above the surface of the ground so that upon the subsequent withdrawal of the casing and the filling in by the concrete of the cavity left thereby, the upper surface of the concrete will be approximately flush with the surface of the ground. The ram is once more inserted in the casing and allowed to rest upon the surface of the column of plastic foundation material therein, and the casing withdrawn while the ram moves downwardly therein so as to compact the concrete and to spread it into the cavity left by the withdrawal of the casing. In certain instances the weight of the ram itself will be sufficient to cause this compacting and spreading of the concrete while in other instances extra pressure will be applied thereto, as by allowing the hammer of the pile driver to rest against the cushioning block 20 while the casing is withdrawn. It will be observed that by thus maintaining the concrete under pressure during the withdrawal of the casing the concrete is pressed into the cavity left by such withdrawal and against the walls of the surrounding soil immediately upon such withdrawal, so that there is no opportunity for these walls to break down and for the soil to fall against and mix with the concrete in a manner as might otherwise weaken the upper portion of the pile.

As the base 17 of the ram reaches the lower end of the casing, the flange 15 will engage the shoulder 19 so that a continuation of the upward movement of the casing will carry the ram therewith. Thus the casing and ram may be moved together to the posi-

- tion at which the next pile is to be formed, placed together upon the ground and again sunk by the application of force to the cushioning block 20.
- 6 There will be formed by the above described method a composite pile such as illustrated in Fig. 8 which extends in a substantially straight—and usually in a vertical—line from the strata of firm soil 25 to 10 the surface of the ground. This pile will consist of a lower member, which will usually be of wood, and an upper member, which in the present instance is formed of concrete and which surrounds the upper end of the 15 lower member so as to positively interlock these elements against relative movement.
- Since certain changes in carrying out the above process, and certain modifications in the article which embody the invention, may 20 be made without departing from its scope, it is intended that all matter contained in the above description or shown in the accompanying drawings shall be interpreted as 25 illustrative and not in a limiting sense.
- It is also to be understood that the following claims are intended to cover all of the generic and specific features of the invention herein described, and all statements 30 of the scope of the invention which, as a matter of language, might be said to fall therebetween.

Having described my invention, what I

claim as new and desire to secure by Letters Patent is:

1. The method of forming a pile which includes ramming a casing into the ground, withdrawing the ram, introducing, a solid pile member into said casing, projecting said ram to drive the member through said casing and into the soil beneath the same, withdrawing the ram, introducing a charge of plastic material into the casing, causing said ram to bear against the surface of such charge, and withdrawing the casing.
2. The method of forming a pile which includes ramming a hollow casing into the ground, withdrawing the ram, introducing a solid pile member into said casing, projecting said ram to force said member through the casing and into the ground beneath the same, retracting the ram, introducing a charge of plastic material into the casing, causing the ram to bear against the upper surface of said charge, and partially withdrawing the casing to form an enlarged portion adjacent the upper end of said member, and subsequently withdrawing the casing to provide an upper pile member having a body substantially equal in area to the cross-sectional area of said casing and less than the area of said enlarged portion.

In testimony whereof I affix my signature.

DONALD McGREGOR NEWTON.
